UNITED STATES PATENT OFFICE.

CHARLES W. DAKE, OF CHICAGO, ILLINOIS, ASSIGNOR TO THE PYLE-NATIONAL COMPANY, OF CHICAGO, ILLINOIS, A CORPORATION OF NEW JERSEY.

HEADLIGHT CASING.

Application filed August 11, 1922. Serial No. 581,081.

To all whom it may concern:

Be it known that I, CHARLES W. DAKE, a citizen of the United States, residing at Chicago, in the county of Cook and State of Illinois, have invented a certain new and useful Improvement in Headlight Casings, of which the following is a specification.

This invention relates to light casings and particularly to a casing for locomotive headlights. It has for one object to provide means whereby the headlight may be readily adjusted so that the beam may be directed at the point desired. Another object is to provide a safety latch whereby the door of the casing may be readily locked by merely shutting the same, but which cannot be accidentally opened. Other objects will appear from time to time throughout the specification and claims.

20 My invention is illustrated more or less diagrammatically in the accompanying drawings, wherein:

Figure 1 is a side elevation of the headlight casing;

25 Figure 2 is an elevation looking from the rear;

Fig. 3 is a partial vertical cross section on an enlarged scale taken on line 3—3 of Figure 2;

30 Like parts are designated by like characters throughout.

A is the headlight casing having the enlarged forward portion A' within which the reflector and lighting element are mounted.

35 The front of the headlight casing is closed by a hinged door B. The rear of the casing is preferably closed as shown and has downwardly depending therefrom a lug C which is provided with an enlarged opening C'.

40 Downwardly and rearwardly extending from the enlarged portion of the casing are a pair of supporting lugs D, D' which are perforated and have mounted within them a shaft D' upon either end of which is mounted a nut D², D'².

45 Beneath the casing and arranged for engagement with the top of the locomotive or more particularly with a bracket fastened on the top of the locomotive is a supporting frame E provided with a plurality of attaching feet E, E'. This member E has two substantially vertical sides as shown.

50 In one of these sides is a slot E² and opposite it in the other end is a round perfora-

tion. For some purposes slots may be used 55 in both sides, of the member E. The shaft D' extends through the slots or slotted perforation and by means of it the casing is pivotally supported at its forward end by the member E.

50 Projecting rearwardly from the frame E is a member F in which there is screw threaded a locking screw G which has mounted upon it a washer G'. Spaced laterally from the screw G and screw threaded 65 also in the part F is a vertical adjusting screw H provided with a locking nut H'.

As shown the screw G lies within the large perforation C' and when it is tightened the washer G' bears against the lug C, thus holding 70 the casing in place.

75 Located within the headlight is any suitable light source not here shown as it forms no part of the present invention. There is also located within the casing a reflector I held in position in any suitable manner, and the front door B has located within it a transparent glass covering B' which is held in position in the door by means of packing B². The sides of the casing are provided 80 with doors J, each of which has a transparent panel J'. The doors are hinged at their tops as at J² and provided with adjustable locking means J³ adjacent their bottom.

85 The door B is hinged at B³ as shown and is provided on its opposite side with a locking latch. The latch is composed of a handle K which is pivoted on the door at K' and provided with an upper extension K² and a hook shaped locking and engaging member 90 K³. This member engages a pin L on the casing. Pivoted upon this pin is a locking dog M. This dog is provided on its inner face with an inwardly extending projection M' adapted when in the locking position to 95 contact the lower face of the hook K³ and adapted when it is desired to open the latch to be swung up out of the engaging position.

100 Although I have shown an operative device, still it will be obvious that many changes in size, shape and arrangement of parts may be made without departing materially from the spirit of my invention, and I wish therefore that my showing be taken as in a sense diagrammatic.

105 The upper extension K² of the latch is designed to act as a lever when the latch is opened. Thus as the handle is raised the

2
face of the extension K^2 bears against the pin L with a wedge action and forces the door outward and open.

The use and operation of my invention
5 are as follows:

It is important that the light of a locomotive headlight be directed so as to fall upon the track upon which the locomotive is running, and while there is, of course, some 10 spread of the light it is more satisfactory to have the beam directed so as to fall exactly upon the track. For this purpose it is necessary to provide adjustment of the headlight casing. As shown the headlight casing is 15 pivotally supported adjacent its forward end and vertical adjustment is made by rotation of the adjusting screw at the rear of the casing. When such adjustment is completed the locking screw is loosened and the 20 requisite raising or lowering of the rear of the casing is accomplished by manipulating the elevating screw, and the locking screw is then tightened and the parts are held in position. For right and 25 left adjustment, however, an additional means has been provided. The shaft upon which the forward end of the casing is pivot- 30 ed can itself be somewhat moved. Thus if there be two slots, one in either side of the supporting frame as suggested above, the supporting shaft may be moved forward in one of these slots and rearward in the other, and thus the headlight will be shifted so as to bend to one side or the other to correspond 35 to the direction of movement. For some purposes it is sufficient to have one slot within which the supporting shaft lies and to have at the other end a perforation corresponding in size to the shaft. This perfora- 40 tion permits sufficient play so that the other end of the shaft may be moved forward or back, and thus the casing may be moved so as to point either to the right or to the left. 45 In case of adjustment either laterally or vertically the rear holding screw is loosened to accomplish the adjustment and is then tightened to hold the parts in the desired position.

When the parts of the latch are as shown 50 in Figure 1 the latch cannot be accidentally opened nor can it be opened by mere manipulation of the handle. It is necessary to swing the locking dog up so that it can no longer engage the hook of the latch, then 55 the latch handle may be rotated so as to bring the latch out of engagement and permit opening of the door.

I claim:

60 1. In combination in a locomotive light, a light casing and a supporting bed upon which it is mounted and means for adjusting the casing vertically and laterally with relation to said bed, said means including slots in the side of and adjacent the forward end of said bed, and lugs on said cas-

ing adapted to be supported from said slots to permit vertical pivotal movement of the casing with relation to the bed and adapted to be moved lengthwise from said slots to permit lateral rotation of the casing. 70

2. In combination in a locomotive light, a light casing and a supporting bed upon which it is mounted and means for adjusting the casing vertically and laterally with relation to said bed, said means including slots 75 in said bed and lugs on said casing adapted to be supported from said slots to permit pivotal movement of the casing with relation to the bed and adapted to be moved lengthwise along said slots to permit lateral rotation of the casing, and an additional locking lug on said casing and a lug on said bed and means for securing the two together 80 in a plurality of adjusted positions. 85

3. In combination in a locomotive light, a light casing and a supporting bed upon which it is mounted and means for adjusting the casing laterally with relation to said bed, said means including a plurality 90 of pivotal connections between said bed and said casing, the pivot points of said connections adapted to be shifted in a generally horizontal plane. 95

4. In combination in a locomotive light, a light casing and a supporting bed upon which it is mounted and means for adjusting the casing laterally with relation to said bed, said means including a pivotal connection between said bed and said casing, the pivot points of said connection adapted to be shifted in a generally horizontal plane 100 and a connection in the rear of said casing for locking the same in adjusted position with relation to said bed. 105

5. In combination in a locomotive light, 105 a light casing and a supporting bed upon which it is mounted, the bed provided with a pair of slots adjacent its forward end and the casing provided with a pair of lugs adjacent its forward end adapted to form 110 pivotal support for the casing from said slots, the casing provided with a lug in its rear and the bed provided with a corresponding lug and the two adapted to be locked together in a plurality of adjusted 115 positions. 120

6. In combination in a locomotive light, a light casing and a supporting bed upon which it is mounted and means for relatively 125 adjusting the two, said means including slots adjacent the forward end of said bed and lugs adjacent the forward end of said casing adapted pivotally to support the casing from said slots, a lug in the rear of said bed provided with an adjusting screw adapted to raise and lower the rear of said casing with relation to said bed, a lug in the rear of said casing and a second lug in the rear of said bed, the two adapted to cooperate and to be secured together in a plurality of 130

adjusted positions to lock the casing to the bed.

7. In combination in a locomotive light, a light casing and a supporting bed upon which it is mounted and means for adjusting the casing with relation to said bed, said means including slots in said bed and lugs extending from said light casing, said lugs being supported from said slots by means of ⁵ stub shafts extending through them and

through said slots, the shafts adapted to be ¹⁵ moved laterally along said slots and provided with means for fixing them in a variety of adjusted positions in said slots, and a connection in the rear of said casing for supporting and locking the same.

Signed at Chicago, county of Cook and State of Illinois, this 8th day of August 1922.

CHARLES W. DAKE.
